CONSTRUCTION MEMBER

Carl G. Muench, Wilmette, Ill., assignor to Celotex Corporation, Chicago, Ill., a corporation of Delaware

Application July 28, 1941, Serial No. 404,322

5 Claims. (Cl. 20—5)

This invention relates to a construction member used in building construction and in particular relates to a corner member used in connection with the application of the so-called insulated brick siding. Generally speaking, insulated brick siding comprises a fiber insulation board base member on a surface of which there is secured a surfacing sheet or applied a coating in which is embedded suitable granules to more or less simulate the appearance and texture of brick, and provided in one way or another with a simulation of mortar joints outlining individual brick faces. In some cases, instead of such facing simulating brick, it is made to simulate stonework or the like.

In the past in connection with various of the insulated brick sidings, the corner members that are used to carry the construction around corners have given trouble, due to the fact that commonly the surface simulating coating applied has been applied to the fiber insulating board base sheet while flat, the such sheet subsequently being bent or folded to provide two diverging sides at right angles, one to the other. It has been common that when these corners are bent or folded in their formation for the outer surface coating to more or less crack over the fold, which is detrimental to the appearance of the material and is also a disadvantage in use in that such a crack may allow access of the elements to the fiber insulating board base sheet, causing deterioration thereof.

The invention is disclosed in particular in connection with a rigid corner unit as above referred to, designed particularly for use in connection with insulated brick siding, but of course, it will be understood that a corner unit embodying the invention hereof, may be used in connection with surface coverings other than insulated brick siding.

One of the objects of the invention is to provide a corner unit as above generally described, which will be weather proof and fire resisting and which may have an attractive decorative surface of such design and configuration as it may be desired to provide thereon.

A further object of the invention is to provide a corner unit of the general character described, that may be produced economically, is of rugged construction and is resistant to the deterioration, which has been more or less common, arising from the cracking of the surfacing material directly over the corner as was above mentioned.

A still further object is to provide a rigid corner unit of the type described, which may be applied

either as an overlay or may be applied in the same planes as those of the surfaces of an insulated brick siding installation connected by such corner members.

5 A still further object of the invention is to provide a method of manufacture of the corner units of this invention, which will produce such units without the cracking of the surfacing material over the corner fold and according to which method, the units may be rapidly produced with a minimum of equipment and labor.

Other and further objects and advantages of this invention will appear upon reading the following specification, wherein the construction and the method of manufacturing of the corner units hereof are set out in detail.

In the drawing accompanying this specification;

Figure 1 is a perspective of a portion of a corner unit;

Figure 2 is a cross section through a base sheet prepared for succeeding steps in the manufacture of a corner unit, and Figure 3 is a diagrammatic illustration of the steps involved in the manufacture of the corner units.

In the drawing accompanying this specification, in the various figures, like numerals will be used to designate like parts.

In the drawing an insulating brick siding corner member is illustrated in Figure 1, comprising a fiber insulating board base 10, on the outer face of which is applied a surfacing 11. The surfacing 11, as illustrated, represents brick work and is obtained through adhering suitable granular material to the outer face of base 10. The adhered granular material comprising surfacing 11 has provided therein suitable mortar joint lines, so that surfacing 11 comprises a simulation of brickwork. So far as the specific nature of the granular material adhered to base 10 to provide the surfacing 11 is concerned, it is relatively immaterial in this description, but it will of course, be understood that the granules are to be selected so that the appearance which is desired for the finished product may be obtained.

It is of course, immediately apparent on viewing Figure 1, that the corner member comprises two portions arranged in right angle relation extending outwardly from a common apex to form an outside corner, and it is of course, immediately apparent that while the corner member shown is illustrated as a 90° corner, that the inventions disclosed in connection therewith are applicable to corner members for other than 90° corners,

that is, such a corner member may be formed to fit a 60° corner or a 120° corner or other corners as may be required.

The corner unit is preferably provided with suitable shiplap edge construction, particularly along its top and bottom edges, but it will of course, be understood that the side edges may be suitably shiplapped, or that if desired, the complementary edges may instead of being shiplapped, be provided with any other suitable closing joint, as for example, with complementing tongue and groove joints.

In manufacturing one of these corner units, the preferred construction and method of manufacture is as follows:

The base sheet for the unit, a fiber insulating board 10, is approximately centrally of its width grooved at 15, and on its other face opposite groove 15, provided with a small groove 16. The function of the grooves 15 and 16 will become apparent as the description of the manufacture of the unit progresses.

After the sheet or fiber board 10 has been grooved, as above described, it is then preferably passed through an asphalt bath by suitably dipping or conveying of the sheet in a pan or tank of molten asphalt.

The asphalt used for this purpose is preferably one of 120° to 140° F., M. P. (ring and ball, A. S. T. M. method) and which has a penetration of about 180 to 200 mm. (100 g., 5 sec., 77° F., A. S. T. M. method).

In dipping the base sheet 10 in asphalt, as described, the time element should be such that the base 10 is given what is termed a surface saturation with asphalt, that is the time of immersion should be sufficient that the asphalt can penetrate into the surface of the base 10, but insufficient for the penetration to progress appreciably throughout the fiber board. The preferable penetration is one wherein the surface portion of the base sheet 10 is well saturated, but with this saturation not extending into the sheet more than approximately $\frac{1}{8}$ " from the exterior uncut broad face of the sheet. In connection with such a saturation along the edges where the sheet of fiber board has been cut, and at the grooves 15 and 16, at which points the structure of the board is more open than on the broad uncut faces, the penetration will be somewhat greater, in general twice the penetration of that at the broad uncut faces.

In the process of dipping the base sheet 10 in the asphalt bath, as above described, due to the fact that a portion of the thickness of the base sheet 10 has been cut away by the provision of grooves 15 and 16 and further because of the greater penetration of the asphalt at these cuts, the base sheet 10 will be more heavily saturated in that portion between the grooves 15 and 16, and in fact, it is preferred that the saturation shall be sufficient that at and between grooves 15 and 16 the fiber board sheet shall be saturated with asphalt throughout its thickness. The portion of the sheet 10, which is fully saturated, as has just been referred to, is designated by the numeral 17. The function served by the completely saturated portion 17 will be more fully described in connection with the further processing of the surface saturated blank.

Base sheet 10, after it has been given a surface saturation with asphalt, as above described, is subsequently processed to form a corner member in accordance with the diagrammatic illustration of the processing as such appears in Fig-

ure 3 of the drawing, and in connection with which the various steps of the processing are as follows:

5 A blank 10, surface saturated as above described, is placed on a suitable conveyor or the like 20, which may carry the blank through the following processing steps.

The blank 10 is placed on the conveyor 20 with that face having groove 16 therein being exposed 10 upwardly, the face with groove 15, being of course, consequently facing downwardly. To the upper face of the blank there is applied an asphalt coating which is preferably a somewhat harder asphalt than that with which the surfaces 15 of blank 10 have been saturated, and which asphalt coating may comprise asphalt of 180° F., M. P. The asphalt coating may be applied to the upper surface of the base sheet 10 in any suitable manner, but for the purposes of the 20 diagrammatic illustration hereof, there has been shown an asphalt discharge pipe 21, which discharges molten asphalt on the top surface of the blank 10, whereupon the asphalt may be squeegeed or spread over the surface of the 25 blank as it passes under the knife 22 of a knife coater, which is a well known piece of equipment used for applying various coatings to various sheet form materials. It will be noted that in applying the surface coating of the asphalt to the upper face of the base sheet 10 as described, that groove 16 will be filled with this coating, that is, at groove 16, the coating will have an extra thickness, due to the fact that groove 16 has been filled with the asphalt.

35 After the asphalt coating has been applied, as just described, suitable granular or gritty material may be discharged onto the surfaces of this coating from a hopper 23, whereupon as the base sheet continues to advance, it will pass under a 40 pressing roll 24, which will press the granular material into the soft asphalt coating. After the surfacing granular material has been pressed into the asphalt coating, the sheet may then pass under a further roll 25, on the surface of which 45 may be provided suitable dies for impressing in the surface suitable mortar joint lines or the like.

The various steps of the processing just above 50 set out are substantially identical with the various steps normally employed by various manufacturers of insulating brick siding units and are also being substantially those commonly used in the manufacture of roll roofing. It is believed that the various steps are well known to those having knowledge of the art, and therefore the 55 description of these steps of the processing have been given only in the briefest manner.

After the various steps of the processing as 60 above described, and while the surfacing 11 on the thus far flat base sheet 10 is still warm and soft, the blank is subjected to a further operation to form the desired corner base with sides or legs outwardly diverging from a common apex, as is shown in Figure 1 of the drawing. Provision may be made for applying in recess 15 a suitable 65 high melting point asphalt, say one of 220° F., M. P. to serve as an adhesive, or if desired, any other suitable adhesive or none at all may be applied in groove 15. For forming the flat base sheet 10 as a corner member with its diverging sides, there is provided a jig 30, which as shown, 70 may be a flat sheet 31 of board or other suitable material having on the upper surface thereof, suitable restraining members, parallel and spaced apart, such restraining members being indicated by numbers 32. For any specific cor-

ner piece, it will of course, be understood that the restraining members are properly spaced on board 31 so that the corner piece will be held to its proper form when folded.

In forming the corner base, the flat blank 10, while the surfacing 11 is still soft, as was above mentioned, is taken off of conveyor 20 and one edge is placed against one of the restraining strips 32, the sheet is then folded at its weakened or hinging portion, that portion between the grooves 15 and 16, the completely saturated portion 17 serving as a hinging connection. As the sheet is folded to its proper form, the other edge of sheet 10 will be entered behind the other restraining member 32, and as will be understood, the folded corner strip will be thereby held and retained in its proper form.

Attention is directed to the fact that when the base member 10 is folded as has been described, it is apparent, the surface of sheet 10, having been removed by the provision of groove 16, that there will be no surface fibers of sheet 10 at this point to be pulled apart from one another directly under the outer corner of the folded corner piece. Instead, since there has been provided an excess thickness or reservoir of the coating asphalt provided by the provision of groove 16, and this asphalt is still soft, it follows that there is merely a tendency for this asphalt to flow slightly as the bend is made with a consequent slight thinning of the thickness of the coating at this point, but without any tendency for cracking.

The particular advantage of the method of formation of the corner piece as has been described, is the avoidance of the tendency of the base sheet 10 to crack, at its outer face as the fold is made, without groove 16 having been made in that face. Also due to the fact that the base sheet 10 has been saturated throughout at its thin portion 17, this portion tends to serve as a hinge when the sheet is folded rather than to allow a sharp break which would occur if this saturated hinged portion were not provided. It will of course, be understood that the deeper groove 15 which was cut into the face of the base sheet 10 on the side opposite of the groove 16, enables one to fold the sheet 10 in accordance with the above.

The corner member after it has been folded, as above described, may then be set aside or carried along on the conveyor and cooled, and if desired, a reinforcing strip of fabric or suitable asphalt saturated felt, and indicated at 35, may be suitably adhered in the interior of the fold of the otherwise completed corner member, and such strip 35 if applied, serves as an added reinforcement, as will be well understood.

So that the most important advantage of the improvement comprising the invention hereof may be clearly understood, attention is directed to the following:

The base sheet 10 ordinarily used in making insulated brick siding and of course, likewise used in making corner members therefor, is fiber insulation board generally $\frac{1}{2}$ " in thickness. In the past, corner members have been made either by cutting a suitable V notch into the back of a sheet, such cut extending entirely through the sheet excepting the outermost face portion thereof, or in the manufacture of corner members, such have been made from two separate pieces of fiber insulation board with complementary edges suitably beveled to provide for the desired angularity of the finished corner mem-

ber. Where the corner member has been made from a sheet provided with the V notch extending substantially through the sheet, it has been common that as the corner was folded, the fibers at the outer surface would pull apart and consequently would pull apart the asphalt surface coating to form a crack in the granules or like surface material embedded in the asphalt coating; such crack appearing directly at the apex of the corner.

In making a corner member from two separate pieces of the base sheet 10 with these pieces complementally beveled and provided on the exterior with a joining and hinging tape or the like, it has been common that when folding such to form corner members, the asphalt surface coating and embedded granule material are attenuated directly over the apex of the corner with the consequent formation of a crack directly over the apex.

In the construction hereof, due to the provision of groove 16, there is provided directly over the apex of the corner what might be termed a reservoir of the asphalt coating, and as the corner member is folded this reservoir, provided with what might be termed a cushion, provides a reservoir of the coating asphalt, which reservoir of asphalt, as the corner is folded, tends to be, in effect pushed out of the recess due to the action of the hinging portion 17 to compensate for attenuation in the surface coating, which would otherwise tend to crack over the apex of the fold were this reservoir of the asphalt coating not provided. By the utilization of the invention hereof, it has been found possible to make strong and rigid corner members which show no tendency to crack over the apex of the corner, and these corner members have in use proved much superior to brick siding corner members made by other methods.

It is, of course, understood that while fiber insulation board has been particularly mentioned as the base material for this corner member, that other suitable sheet form material may be used, and that whereas asphalt has been particularly referred to as the surface saturant for the base sheet, and as the coating in which the granules surfacing material is embedded, that other suitable substances, such as various pitches and the like may be substituted therefor, and that other like substitutions in connection with the manufacture of the brick siding corner members may be availed of without departing from the spirit of my invention.

The invention hereof having been described in detail, what I claim is:

1. A building corner member comprising a fiber board sheet bent to provide two legs diverging from a common apex, the fiber board portions forming the two legs connected by an integral thinned portion of the fiber board sheet substantially completely saturated with a plastic and constituting a hinging connection between the two leg portions.

2. A building corner member comprising a fiber board sheet bent to provide two legs diverging from a common apex, the sheet at the bend having a shallow recess extending inwardly from one face, and a deeper recess extending inwardly from the other face, the recesses opposite one another forming an intermediate portion, the intermediate portion thereof forming a hinging connection connecting the two diverging legs.

3. A building corner member comprising a fiber board sheet bent to provide two legs diver-

ing from a common apex, the sheet at the bend having a shallow recess extending inwardly from one face and a deeper recess extending inwardly from the other face, the recesses opposite one another forming an intermediate portion, the intermediate portion thereof forming a hinging connection connecting the two diverging legs, the hinging connecting portion substantially saturated with an asphaltic material.

4. An insulating corner member comprising a fiber insulating sheet body portion providing two legs diverging from a common apex, the outer face of the corner member coated with a plastic and having surfacing granules adhered thereto, the outer surface of the sheet body relieved along the common apex and an extra thickness of plastic at the apex. 10 15

5. The method of fabricating an insulating building corner member from sheet form fiber insulation board which comprises the steps: providing a folding line on the sheet form fiber insulation board, by opposed grooves, one deeper and wider than the other forming a thin connection portion connecting outwardly diverging leg portions, saturating the resulting thin connecting portion with a plastic and bending the sheet while the plastic is in a softened condition, whereby a corner member comprising leg portions diverging from a common apex and connected by a thin hinging portion is formed.

CARL G. MUENCH.
